UNITED STATES PATENT OFFICE.

JOHN T. CADE, OF ARCOLA, NEW JERSEY, ASSIGNOR TO FEDERAL SIGNAL COMPANY,
A CORPORATION OF NEW YORK.

VEHICLE-CONTROL SYSTEM.

1,231,846.

Specification of Letters Patent.

Patented July 3, 1917.

Application filed September 12, 1912. Serial No. 719,919.

To all whom it may concern:

Be it known that I, JOHN T. CADE, a citizen of the United States, and a resident of Arcola, county of Bergen, and State of New Jersey, have invented certain new and useful Improvements in Vehicle-Control Systems, of which the following is a specification.

This invention relates to vehicle or train control systems and has for its object to eliminate certain dangers to railway traffic which have lately impressed themselves upon the minds of the public and those actively interested in the installation of systems and apparatus of this character. Recently it has been especially realized that many accidents upon railways are due to the fact that engine drivers, for one reason and another, pass the ordinary semaphore signal while in its danger position in disregard of traffic regulations. It is found that such action of engine drivers is frequently due less to a voluntary disregard of the signal than to a failure to note or realize its danger indication.

Heretofore, it has been proposed to meet this condition by providing train stops to positively and automatically stop the train when the engine driver passes or attempts to pass the signal in the danger or stop position. But a train stop is objectionable for reasons peculiar to itself. In the first place it takes from the engine driver his own control of his train under certain conditions and makes him liable to rely upon the automatic stop instead of himself to avoid accidents. This tends to lessen that feeling of responsibility, watchfulness and care which it is essential to preserve in the engine driver. Furthermore, the automatic stop is not well adapted to efficient conduct of traffic where such traffic is carried on under the usual widely varying conditions of ordinary railway operation. A signal sometimes stands at warning indication when it is desirable for traffic reasons that it be passed if this is done with full realization by the engine driver of his act. A stoppage of the train under such conditions by an automatic train stop would serve no useful purpose but would be a hindrance to traffic.

In the present invention the control of the train is not taken from the engine driver

but provision is made to make him exercise increased care against proceeding when travel is dangerous, without full knowledge and realization of his act. It will be understood that travel is dangerous when conditions are such as those now usually indicated by the warning condition of a signal. In accordance with this invention, therefore, the automatic stop is eliminated and in its place there is provided a special alarm device designed to be automatically operated whenever the engine driver proceeds when travel is dangerous or when he enters a danger zone of the track, unless, having noted the danger condition of the track, he first performs some act, or requires some other person to perform some act, that will forstall the operation of the alarm device. If he has noted the danger to travel, on the track ahead, and finds it advisable to proceed, notwithstanding, he is at liberty to do so provided he first performs some act, or requires some other person to perform some act, that will cut out the alarm device from operation. But if, with inattention and lack of watchfulness, he proceeds when travel is dangerous or into the danger zone, he will fail to cut out the alarm device, and it will operate and thereby cause others, and preferably him also, to realize what is taking place. This alarm device is distinct in its action or appeal from that of the bell, whistle or other signal usually carried on a train or vehicle, being designed and arranged to attract the attention of occupants of the vehicle or train other than the vehicle operators, such as the engine driver and fireman of a steam locomotive or the motorman of an electric car or train. The alarm device is also preferably designed and arranged to attract the attention of such operators of the vehicle or train in addition to that of the occupants, such as the passengers and such as the train crew other than the operators. Thus, the control of the train is left with the engine driver but he is induced to exercise increased watchfulness and is made to realize the consequences of his act when entering or about to enter a danger zone of the track.

In the preferred arrangement a signal is employed to indicate to the engine driver when travel is dangerous and it is arranged to give its warning at the entering end of

a track zone when travel in such zone is dangerous. It is obvious that the signal with which the alarm device is associated may be a full stop or a cautionary signal. In either case, when the signal gives its warning indication, it is to be understood that the track zone guarded by the signal is "dangerous" or is a "danger zone" as these terms are herein used.

10 The invention may be embodied in various forms. It is not restricted to any special type of alarm device nor any special type of signal device. This alarm device may be stationed on the trackway or it may be located on the engine or at other points on 15 the train. Nor is the invention to be restricted to any special means for controlling or operating the signal or alarm device.

10 The invention is shown in one of its various embodiments in the accompanying drawings.

Referring now to this particular embodiment of the invention, as shown in the drawing, T^1 and T^2 are two track sections, each 25 of which is provided with the usual rail circuit, the former including track battery TB^1 and track relay R^1 , and the latter including track battery TB^2 and track relay R^2 . T^3 is a track section in advance of 30 track sections T^1 and T^2 . A is a signal which may be of the usual semaphore type as shown and operated by a solenoid whose 35 coil is E and core F . The signal is located at the entering end of track section TB^1 and therefore serves to protect this track section and the following portion of the track. As 40 shown in the drawing, the alarm device is in the form of an audible signal. But it may address itself to the intelligence in any suitable manner, audible or otherwise. In 45 the present instance, it is shown as consisting of a gong G adapted to be struck by a solenoid striker Y having a coil X . This gong is suitably housed and stationed on the trackway in proximity to the signal A .

One terminal of the solenoid E is connected with the generator SB and the other pole is connected through contact point 1, contact finger 2 and wire 3 with the other 50 pole of this generator. Contact finger 2 is operated by coil of relay R^1 . M and N are two contact rails extending parallel with track section T^3 , the former being connected by wire 23 with contact 24 and the latter 55 being connected with contact 22 by wire 25. Contact rail N is also connected by wire 14 to one pole of the generator SB and contact rail M is connected through wire 15, coil of relay R^2 and wire 16 to the opposite pole of 60 generator SB . Contact rail N is also connected through wire 17, contact finger 18, contact point 27, wire 19, contact finger 20 and wire 21 to wire 15. Solenoid coil X is connected on one side by wire 5 to contact 65 point 30, and contact point 29 is connected

by wire 4 to one side of generator SB . On its other side, this coil X is connected through contact finger 7, contact point 8, wire 9, contact point 6, contact finger 10, wire 11, contact point 26, contact finger 12 70 and wire 13 to the opposite side of the generator SB . C and D are two contacts carried on the blade of signal A . Contact C is adapted to connect contact points 29 and 30 when the signal is in danger position. Contact D is adapted to connect contact points 24 and 25 when the signal is in safety or proceed position. Contact fingers 12 and 18 are operated by coil of track relay R^2 . Contact fingers 10 and 20 are operated by coil 80 of relay R^1 . V^1 is a car on the track provided with a pivotally mounted contact shoe K normally elevated above the level of the contact rails M and N but adapted to contact with and bridge the contact rails M and N when the engine driver depresses the treadle J . V^2 is a car similarly provided 85 with a shoe K .

In the normal condition of the system, that is when there are no cars on the track, 90 the track magnets R^1 and R^2 are energized. The former serves to hold normally closed the circuit through solenoid coil E so that signal A is normally held in safety or proceed position with contact points 24 and 25 95 bridged by contact D . This serves to open the circuits of which the contact fingers 12 and 18 are a part. Magnet R^2 is normally energized and its contact fingers held in elevated position. The normally closed circuit 100 of magnet R^2 may be traced from battery SB , through wire 14, contact rail N , wire 22, contact point 25, contact D , contact point 24, wire 23, contact rail M , wire 15, magnet R^2 and wire 16 back to battery. It will be seen 105 that in the normal condition, the circuit of the alarm device or gong G is normally broken at contact points 29 and 30 and also at contact fingers 10 and 12.

The operation of the system is as follows. 110 When a train reaches track section T^3 and the signal is at safety, the train proceeds on to track section T^2 , thereby deenergizing magnet R^2 and dropping its contact fingers 12 and 18. This produces no effect upon the alarm device because its circuit is still broken at contact points 29 and 30 and contact finger 10. When the train enters on track section T^1 , it deenergizes coil of relay R^1 thereby opening the circuit for the signal and permitting it to move to danger position behind the train. In the drawing the train V^2 is shown occupying track section T^1 with the consequent result that the signal is in danger position, closing contacts 125 29 and 30 and opening contacts 24 and 25. The opening of contacts 24 and 25 breaks the circuit of magnet R^2 and drops contact fingers 10 and 20. When now the following train V^1 enters track section T^3 , the engine 130

driver may stop his train in response to the danger indication of the signal. If he fails to note the signal and carelessly proceeds, then when his train reaches track section 5 T^2 , it deenergizes magnet R^2 and closes the circuit of the gong G^2 or other alarm device and sets it in operation. This circuit may be traced from battery SB, through wire 4, contacts 29, C and 30, wire 5, coil X, contacts 10 7 and 8, wire 9, contacts 6 and 10, wire 11, contacts 26 and 12, and wire 13 back to battery. The operation of the alarm device attracts the attention of the engine driver and makes him aware of the fact that he 15 is negligently passing the signal in danger position. As already stated, the character of warning produced by the alarm device is so distinctive that it not only attracts the attention of the engine driver but also attracts the attention of the train crew and 20 passengers so that the negligent act of the engineer is known to other persons on the train who may operate the engine whistle or apply the emergency brake. If, however, 25 when the train V^1 reaches track section T^3 with the signal at danger and the engine driver desires to pass the signal in this position, he may then depress the shoe K so as to bridge contact rails M and N and there- 30 by close the circuit through magnet R^3 . This opens the alarm circuit at contact finger 10 and closes contact finger 20 with its contact point. The train then proceeds on to track section T^2 whereupon magnet 35 R^2 is deenergized thereby closing contact finger 12 with contact point 26 and contact finger 18 with contact point 27. This action of track magnet R^2 takes place before magnet R^3 is deenergized by the passing of 40 shoe K beyond contact rails M and N. For this purpose magnet R^3 may be constructed so as to have a slow release. The result of this action is that magnet R^3 is kept energized by the train in section T^2 even after 45 the train V^1 has passed on to track section T^2 and beyond track rails M and N, the circuit through this magnet being as follows; from battery SB, through wire 14, contact rail N, wire 17, contacts 18 and 27, wire 19, 50 contact finger 20, wire 21, magnet R^3 and wire 16 to battery. When the train passes beyond track section T^2 , magnet R^2 will be restored to normally energized condition and contact fingers 12 and 18 are lifted from 55 their contact points. This action of contact finger 18 breaks the circuit just traced through magnet R^3 which thereupon drops its contact fingers 10 and 20. When a train, as V^2 , moves on to track section T^1 , it sets the signal at danger as heretofore explained, and when it passes beyond this track section and the track portion guarded by the signal, the signal returns to safety position with the circuits and devices in normal condition. 60

The invention may be associated with a signal standing normally at danger as well as with one standing normally at safety, also with a signal located on the train as well as on the trackway and also with a signal whose indication is given otherwise than by changes in position. 70

Instead of providing that the engine driver, himself, may perform the act which forestalls the operation of the alarm device, 75 it may be provided that he must require some one else to perform such act. For example, it may be provided that he must stop to enable the conductor to get off and cut out the alarm device by operating a switch located on the trackway. For this purpose the normally open switch S is shown connected to wires 22 and 23. When the train stops the conductor may close this switch and keep it closed till the train has passed 80 beyond track section T^2 whereupon he may then open it. This produces the same result as the act of the engine driver in depressing shoe K. 85

The term "danger condition" of a signal, 90 as herein used, means a cautionary or any condition other than safety, and may indicate that the train or vehicle should stop immediately or slow down or be prepared to stop. 95

What is claimed and desired to be secured by Letters Patent is:—

1. In a vehicle control system, the combination of an alarm device distinct in its action from that of the signals usually carried on a vehicle or train and designed and arranged to attract the attention of occupants of the vehicle or train other than the operators thereof; a signal on the trackway controlling said alarm device; vehicle controlled means for operating the alarm device; and means operable from the vehicle for preventing the operation of said alarm device. 100 105

2. In a vehicle control system, the combination of an alarm device located on the trackway and controlled by the condition of a portion of the track in advance of said alarm device; vehicle controlled means for operating the alarm device; and means operable from the vehicle for preventing the operation of said alarm device. 110 115

3. In a vehicle control system, the combination of an alarm device distinct in its action from that of the signals usually carried on a vehicle or train and designed and arranged to attract the attention of occupants of the vehicle or train other than the operators thereof; a signal on the trackway controlling said alarm device; a track circuit controlling said alarm device; and means operable from the vehicle for preventing the operation of the alarm device. 120 125

4. In a railway train control system, the combination of a signal guarding a portion 130

of the track; a track circuit controlling said signal; an alarm device controlled by the signal and operable when the signal is in a predetermined condition of indication, said alarm device being distinct in its action from that of the signals usually carried on a vehicle or train and designed and arranged to attract the attention of occupants of the vehicle or train other than the operators thereof; a track circuit controlling said alarm device; and means for preventing the operation of the alarm device.

5. In a vehicle control system, the combination of a signal; an alarm device controlled by the signal and operable when the signal is in a predetermined condition of indication, said alarm device being distinct in its action from that of the signals usually carried on a vehicle or train and designed and arranged to attract the attention of occupants of the vehicle or train other than the operators thereof; vehicle controlled means for operating the alarm device when the signal is in said condition of indication; and means operable from the vehicle for preventing the operation of the alarm device.

6. In a vehicle control system, the combination of a signal located on the trackway; an alarm device located on the trackway and operable when the signal is in a predetermined condition of indication; vehicle

controlled means for operating the alarm device when the signal is in said condition of indication; and means operable from the vehicle for preventing the operation of the alarm device.

7. In a railway train control system, the combination of a signal guarding a portion of the track; a track circuit controlling said signal; an alarm device controlled by the signal and operable when the signal is in a predetermined condition of indication; a track circuit controlling said alarm device; and means operable from a train for preventing the operation of the alarm device.

8. In a railway train control system, the combination of a signal stationed on the trackway and guarding a portion of the track; a track circuit controlling said signal; an alarm device stationed on the trackway and operable when the signal is in a predetermined condition of indication; a track circuit controlling said alarm device; and means operable from a train for preventing the operation of the alarm device.

In testimony whereof, I have signed my name to this specification, in the presence of two subscribing witnesses.

JOHN T. CADE.
